Primary Examiner — Susan Moon Lee(74) *Attorney, Agent, or Firm* — Polsinelli PC**CLAIM**

The ornamental design for a fill component of a bird feeder, as shown and described.

DESCRIPTION

FIG. 1 is a front environmental perspective view of a fill component of a bird feeder showing our new design; FIG. 2 is a front perspective view of the fill component of a bird feeder;

FIG. 3 is a side perspective view thereof;

FIG. 4 is an elevational view thereof;

FIG. 5 is a side elevation view thereof;

FIG. 6 top plan view thereof; and,

FIG. 7 is a bottom plan view thereof.

Broken lines and unshaded portions contained within broken lines are not claimed.
